UNITED STATES PATENT OFFICE.

HARRY J. WATTS, OF TURTLE CREEK, PENNSYLVANIA.

DEVICE FOR DRILLING OR BORING POLYGONAL-SHAPED OPENINGS.

Application filed January 14, 1921. Serial No. 437,153.

To all whom it may concern:

Be it known that I, HARRY J. WATTS, a subject of the King of England, residing at Turtle Creek, in the county of Allegheny and State of Pennsylvania, have invented certain new and useful Improvements in Devices for Drilling or Boring Polygonal-Shaped Openings, of which the following is a specification.

- 10 This invention relates to a device for boring or drilling polygonal-shaped openings, of hexagonal shape and has for its object to provide a device of such class, in a manner as hereinafter set forth, with means to allow 15 the tool-element of the device, to travel in a path corresponding to the length and angles of a polygonal figure, having any desired number of lines or angles, when boring or drilling a polygonal-shaped figure whereby 20 the opening drilled or bored will correspond to the shape of the figure.

A further object of the invention is to provide a device of such class, in a manner as hereinafter set forth, with a chuck element 25 to control the floating action of the tool-element during the operation of the device, and to provide the chuck-element with means for governing the floating action imparted by the chuck-element to the tool-element.

30 A further object of the invention is to provide a device of such class, in a manner as hereinafter set forth, with means for reducing friction to a minimum between the moving or shifting elements of the device, to facilitate a smooth shifting movement of such 35 elements during the operation of the device.

Further objects of the invention are to provide a device of such class which is simple in its construction and arrangement, 40 strong, durable, compact, readily assembled, efficient and convenient in its use, and comparatively inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood 50 that changes, variations and modifications can be resorted to which come within the scope of the claims hereunto appended.

In the drawings wherein like reference characters denote corresponding parts throughout the several views:

Figure 1, is a section on line I—I Figure

2, of a device for boring or drilling polygonal-shaped openings in accordance with this invention.

Figure 2, is a section on line II—II Figure 60 1.

Figure 3, is an inverted plan of the shank carrying member of the chuck-element.

Figure 4, is a top plan view of the tool-element carrying member of the chuck-element 65 1.

Figure 5, is a perspective view of the tool-element for drilling or boring hexagonal shaped openings.

Figure 6, is an elevation of the guide element.

Referring to the drawings in detail a device for boring or drilling polygonal-shaped openings in accordance with this invention comprises a chuck-element, a tool-element 75 and a guide element, the latter associating with the tool-element to provide for the shape of the figure and for guiding the tool-element in lines corresponding to the shape of the figure, and the chuck-element providing for the necessary floating action of the tool-element during the operation of the device so that the function of the tool-element will be satisfactorily performed. The chuck-element is illustrated in connection with a 80 tool-element for drilling or boring a hexagonal-shaped opening, but it is to be understood that the chuck-element can be used with any type of tool element for which it is found applicable.

The chuck-element comprises a shank carrying member, a tool-element carrying member; a combined coupling and enclosing casting, and a float action governor. The shank and tool-element carrying members have associated means to provide for a floating action to be imparted to the tool-element during the operation of the latter.

The shank carrying member of the chuck-element consists of a circular disk 7, provided on its outer face with an integral shank 8, for the purpose of connecting the chuck-element to a driving means for imparting a rotary action to the said element. The disk 7 is provided with peripheral threads 9.

The tool-element carrying member of the chuck element consists of a circular disk 10, of less diameter than the disk 7, and which has its outer face provided with a depending sleeve or collar 11, for the purpose of receiving the tool-element, the latter being

secured to the sleeve 11, by a binding screw 12. The inner face of the disk 10 is formed with a series of grooves 13, arranged in the form of a circle and which provide ball races, for the bearing balls 14. The grooves 13 are much wider than the diameter of the balls 14, but the depth of the grooves 13 is such that the balls 14 will project thereabove, whereby when the disks 7 and 10 are arranged in operative relation relative to each other the disk 7 will rest on the balls 14, and be spaced from that face of the disk 10 in which the ball races are formed.

15 The disks 7 and 10 have associated means to provide for imparting to the tool-element a floating action during the operation of the device, and that part of such means relative to the disk 7 consists of a circular cavity 15, arranged centrally of the inner face of the disk 7, and a series of equally distant and radially disposed recesses 16, which open into the cavity 15. That part of such means relative to the disk 10, consists of a circular offset 17, on the inner face of the disk 10 and which extends into and is of less diameter than the cavity 15. Projecting from the offset 17, is a series of equi-distant and radially disposed arms 18, arranged in pairs, and in each pair of arms is pivotally and eccentrically mounted a roller 19. The pairs of arms and rollers extend into the recesses 16. The edges of the rollers acting against the walls of the recesses 16 will cause the disk 10 to revolve with the disk 7 and further cause a floating action of the disk 10, while revolving, so that the tool element carried by the disk 10, will be caused to travel 40 in a path corresponding to the length and angles of the polygonal-shaped figure of the guide element through which the tool element operates. As the rollers 19 are eccentrically mounted the engagement of the edges thereof with the walls of the recesses 16, at certain points thereof will be constant whereby a continuous revolving and floating action will always be imparted to the disk 10 and tool element.

50 The combined coupling and enclosing casting of the chuck-element is formed from an annular body 20, having its lower end formed with an inwardly extending annular flange 21, through which extends the sleeve 11. The flange 21 is formed with an upwardly disposed annular ridge 22, on which is mounted the disk 10. The function of the ridge 22, is to reduce friction to a minimum during the floating action of the disk 10, and tool-element while the latter is being driven from the disk 7. The body 20 is formed with interior threads which engage with the peripheral threads 9 of the disk 7, whereby the body is connected to the disk 7 and supports and couples

the disk 10 with the disk 7. A binding screw 23 is provided for forcing an abutment member 23' against the body 20 to prevent shifting thereof. The opening formed by the flange 21 is of materially greater diameter than the sleeve 11 and the edge of the flange can be employed to limit the floating action of the disk 10.

For governing the floating action of the disk 10, as well as providing a dust guard a float action governor is provided, and which comprises a collar having its upper portion 24 of greater thickness than the lower portion 25, and projecting from the upper portion 24 of the collar is an annular flange 26 which extends beyond the edge of the flange 21. The float action governor is adapted to be detachably secured to the sleeve 11, as shown in Figure 1, and in this connection the thicker portion of the collar is arranged between the flange 21 and the sleeve 11 and which acts as a means for governing the floating action of the disk 10, but if the floating movement of the disk 10, is desired to be increased, the collar is reversed so that the thin portion thereof will be interposed between the sleeve 11 and the flange 21. In either position of the collar the flange 26 extends beyond the flange 21 and acts as a chip and dust guard, to prevent entrance thereof into the body 20.

95 The guide-element is formed from a plate 27, of any suitable material and which is provided with an opening 28, the walls of which correspond in contour to shape of the polygonal figure or opening to be drilled or bored. As shown the guide member is provided with an hexagonal-shaped opening. When the guide element is in use it is secured to that face of the work 105 to be operated on.

110 The tool-element comprises a body portion 29 and a shank 30, provided with flats 30'. The shank is extended into the sleeve 11, and secured therewith by the binding screw 12 abutting against a flat. The body portion 29 is cylindrical and cutaway to provide three flutes 31, for the passage of chips during the cutting operation. Two of the flutes 31 are provided on one side of the body portion and the other flute 31 on the other side of the body portion and by this arrangement the lands, 32, 32' and 33 are formed, the land 33 being of less width than the other two lands. At the operative end of the tool-element three cutting edges 34, 35 and 36 are provided. The land 33 inclines inwardly and each of the lands 30, 32, is rounded inwardly. That part of the body portion 29 between the flutes at each side of the land 32 is inclined with respect to the cutting edge 35.

115 One wall of each flute at a cutting edge is ground back as at 32a to overcome cutting of rounded corners or in other words it pro-

vides for cutting of sharp corners.

That part of the body portion 29, at the operative end of the tool-element between the flutes at each side of the land 32 inclines 5 downwardly as at 37, with respect to the cutting edge 36, and that part between the flutes at each side of the land 33 inclines downwardly as at 38, with respect to the cutting edge 34. The inclined portions provide 10 clearance to enable free operation of the tool-element and also to prevent clogging of the chips as they will have free entry to the flutes. The cutting edges are so disposed that when the tool-element is in 15 operative position and in connection with the floating action from the chuck a hexagonal shaped-figure will be produced.

I am well aware, that prior to my invention of this tool, that all tools for boring or 20 drilling polygonal shaped openings of hexagonal contour, must be so set up as to have one less cutting lip than the number of walls of the opening to be formed and one less cutting lip than the number of walls of 25 the opening in the tool guide. The tool of my invention for drilling or boring a hexagonal shaped opening is provided with but three cutting lips, whereas heretofore it required five cutting lips. The explanation 30 as to why a three lipped tool, in accordance with this invention, will cut a hex is:— Take a tool with five cutting lips, which are numbered one, two, three, four and five, now 35 remove the lips three and five, which places two lips on one side of the tool and one lip on the other, there is nothing to prevent the remaining lips or edges from following the same course as provided by the tool guide as if the tool had the five lips or cutting edges. 40 When the tool is set up however, with three lands, two of which are of greater length than the other and the cutting edges are arranged on the leading side edges of the lands, the follower side edge of the land of 45 smaller width is in a plane intersecting the inner portion of the leading side edge of one of the lands of greater width and is spaced from the leading side edge of the other land of greater width and the disposition of 50 the leading side edges of the lands provides, in connection with the guide element, for a three lipped tool to form a hexagonal shaped opening during the operation of the tool relative to the work.

55 The device can perform its function whether it is rotated bodily with the work stationary, or the device held stationary and the work revolved, in either case the function performed is the same.

60 What I claim is:—

1. A device for the purpose set forth comprising a chuck-element provided with a revolvable shank carrying member and a floatable tool-element carrying member connected therewith, one of said members pro-

vided in one face with a plurality of radially disposed recesses and the other carrying on one face a plurality of eccentrically mounted pivoted members each moving lengthwise of and operating against the 70 walls of a recess for imparting a floating action to the tool-carrying member during the revolving of the shank carrying member.

2. A device for the purpose set forth comprising a revolvable chuck-element including a pair of disks and having eccentrically mounted radially shiftable pivoted members carried by one disk and bodily and radially shiftable within and travelling against the other of the disks for imparting a floating 75 action to one of the disks during the revolving of the chuck, a tool-element carried by that disk to which the floating action is imparted, and a guide element associated with the tool-element.

3. A device for the purpose set forth comprising a revolvable chuck-element including a pair of disks and further having eccentrically mounted radially shiftable pivoted members carried by one disk and bodily 80 and radially shiftable within and travelling against the other of the disks for imparting a floating action to one of the disks during the revolving of the chuck, a tool-element carried by that disk to which the floating 85 action is imparted, a guide element associated with the tool-element, and means for controlling the extent of the floating action imparted to that disk carrying the tool-element.

4. A device for the purpose set forth comprising a revolvable chuck-element including a pair of disks, one of said disks having a cavity and a plurality of radially disposed recesses projecting from the wall of said cavity and the other of said disk extended into said cavity and carrying a plurality of eccentrically mounted pivoted radially disposed members travelling inwardly and outwardly against the walls of the recesses for imparting a floating action to one of the disks during the revolving of the chuck element, and bearing balls interposed between the disks.

5. A device for the purpose set forth comprising a revolvable chuck element including a pair of disks coupled together and one provided with a plurality of radially disposed recesses and the other with eccentrically mounted pivoted members travelling inwardly and outwardly against the walls of the recesses for imparting a floating action to one of the disks during the revolving of the chuck-element, bearing means interposed between said disks, a tool-element carried by that disk to which the floating action is imparted, and a guide element for the tool-element.

6. A device for the purpose set forth comprising a revolvable chuck element provid-

ed with radially disposed recesses and further including a shiftable member revolving with the said element, eccentrically mounted means forming a part of the chuck 5 element and travelling against the walls of said recesses for imparting a floating action to said member during the revolving of the chuck element, a tool element carried by said member, and a guide element associat- 10 ed with the tool-element.

7. A device for the purpose set forth comprising a revolvable chuck element provided with radially disposed recesses and further including a shiftable member revolving therewith and further including a plurality of eccentrically mounted rollers travelling against the walls of said recesses for imparting a floating action to said member during the revolving of the chuck element, 15 means for governing the floating action of said member, a tool-element carried by said member, and a guide element associated with the tool-element.

8. A device for the purpose set forth comprising a chuck-element provided therein with radially disposed recesses and further including a shiftable member and eccentrically mounted means travelling against the walls of the recesses for imparting a floating 25 action to said member, a tool carried by said member, and a guide element associated with the tool element.

9. A device for the purpose set forth comprising a chuck element provided therein with radially disposed recesses and further 35 including a shiftable member and eccentrically mounted means travelling against the walls of the recesses for imparting a float-

ing action to said member, a tool carried by said member, a guide element associated with the tool element, and means carried by the tool element for governing the floating action of the said member. 40

10. A device for drilling or boring hexagonal shaped openings comprising the combination with a floating tool chuck, and a guide having a hexagonal shaped opening, of a tool carried by the chuck and extending through the guide and provided with a pair of flutes on one side and a flute on the other side of its cutting end thereby forming three lands, two of greater width than the other and with the leading side edge of each land constituting a cutting edge, that land of less width having its 50 outer edge inclined inwardly. 55

11. A device for drilling or boring hexagonal shaped openings comprising a combination with a floating tool chuck and a guide having a hexagonal shaped opening, of a tool carried by the chuck and extending through the guide and provided with a pair of flutes on one side and a flute on the other side of its cutting end, thereby forming three lands two of greater width than the other and with the leading side edge of each land constituting a cutting edge, that land of less width having its outer edge inclining inwardly, the follower edge of the land of less width disposed in a plane intersecting the inner portion of the cutting edge of a land of greater width and spaced by a flute from the cutting edge of the other land of greater width. 60 65 70

In testimony whereof I affix my signature.
HARRY J. WATTS.
